UNITED STATES PATENT OFFICE.

RUSSELL B. KINGMAN, OF ORANGE, NEW JERSEY, ASSIGNOR TO METAL TEXTILE CORPORATION, OF WEST ORANGE, NEW JERSEY, A CORPORATION OF RHODE ISLAND.

DECORATIVE ORNAMENT.

Application filed September 21, 1927. Serial No. 220,923.

This invention relates, generally, to improvements in decorative ornaments for general use, but which are especially adapted for use as Christmas tree ornaments.

5 The invention has for its principal object to provide an ornament which is strong and durable, and of a character not easily broken, and which presents a surface affording a multiplicity of light reflecting facets so as 10 to produce a brilliant scintillating effect when light is directed upon and reflected therefrom.

The invention is clearly illustrated in the accompanying drawings, in which:—

15 Fig. 1 is a view in part section of a base element forming a part of the novel ornament made according to this invention; Fig. 2 is a diagrammatic view of a tubular knit metallic mesh from which the decorative surface element of the device is made; Fig. 3 20 illustrates the manner of preparing said decorative surface element for application to the base element; Fig. 4 is a diagrammatic view of the base element and decorative surface element ready to be assembled together; Fig. 5 is a side elevation of the completed ornament ready for use; and Fig. 6 is a view 25 of the completed ornament with the decorative surface element in section.

30 Similar characters of reference are employed in the above described views, to indicate corresponding parts.

Referring to the drawings, the reference character 10 indicates a base element of suitable shape. This base element is preferably made in the form of a hollow shell comprising two sections suitably secured together. Said shell may be made of metal or any other comparatively rigid material. 35 Said base element may be made in the form of a ball as shown, or it may be made in other shapes if desired.

To provide the decorative surface element for application around and upon the base element 10, I provide a metallic fabric 11, which is initially produced as a tubular knit seamless body or sleeve. The metallic fabric 11 is formed by knitting a flat or ribbon-like metallic strand or wire, the wire being 40 polished or otherwise treated to provide light reflecting surfaces. The tubular knit metallic fabric 11 is applied over and upon the surface of the base element 10, and suitably secured in place, to provide a covering decorative envelope thereupon. Owing to

the fact that in knitting the flat metallic wire, the same is looped back and forth throughout the area of the fabric, and is thereby twisted to present portions of its flat polished surfaces at a great variety of angles, it follows that when light is directed upon the decorative surface element, the same will be reflected from a great multitude of angular facets and will consequently produce a very pleasing sparkling or scintillating effect of considerable beauty. The decorative surface element 11 thus produced and applied upon the base element 10 may consist of one or more plies or thicknesses of the knitted metallic fabric. I recommend, however, a decorative surface element comprising a two-ply cover, since in such form and arrangement thereof a greater multiplicity and more closely distributed arrangement of angular light reflecting facets is obtained. I have therefore illustrated in the drawings the preferred manner of forming and applying such two-ply decorative surface element. To this end I take a suitable length of said tubular knit metallic fabric 11, and gather its intermediate portion together, preferably by twisting the same into a constricted portion 11', as shown in Fig. 2. When thus prepared I turn one end portion back and over upon the other, thus providing a two-ply cover, as shown in Figure 4, one end of which is open and the other end of which is closed by the constricted portion 11'. The base element 10 is now inserted into the cover through said open end, whereupon said open end is gathered together and closed over the base element, as indicated at 12 in Figures 5 and 6. The thus closed end 12 of the cover is secured together, so as to be maintained in closed condition, by wrapping a fastening tie 13 of wire around the same, and at the same time forming in connection with said tie a freely projecting loop 14 to serve as a suspension loop for hanging the completed device upon a Christmas tree, or suspending the same in any other connection wherein its ornamental effect is desired.

It will be understood that the decorative surface element may be treated with color if desired, i. e. the flat wire may be enameled or otherwise coated with coloring material where color effects are desired. It will also be understood that the surface of the base element 10 may have suitable coloring ma-

aterial applied thereto, so that the color effect will be visible through the meshes of the overlying decorative surface element 11.

From the above description it will be obvious that the instant invention provides a novel form of decorative ornament especially adapted for use as a Christmas tree ornament; and, furthermore, that since the same may be made of all metal construction it provides a strong and durable device, which is not easily broken by accident, as is so frequently the case with fragile Christmas tree ornaments made of glass such as are commonly provided.

I am aware that some changes and modifications may be made in the above described construction and arrangement of elements making up the novel decorative ornament, without departing from the principles or scope of this invention, and consequently it is intended that all matter contained in the above description or shown in the accompanying drawings shall be interpreted as illustrative and not in a limiting sense.

I claim:—

1. A decorative ornament, comprising a substantially rigid base element of desired shape and a decorative surface element enveloping said base element, said surface element consisting in a metallic fabric knitted from flat ribbon-like wire to provide a multiplicity of light reflecting facets.

2. A decorative ornament for the purposes described, comprising a substantially rigid base element of desired shape and a decorative surface element enveloping said base element, means to secure said surface element relative to said base element, and a suspension loop connected with said surface element, said surface element consisting in a metallic fabric knitted from flat ribbon-like

wire to provide a multiplicity of light reflecting facets.

3. A decorative ornament for the purposes described, comprising a substantially rigid base element consisting in a hollow metallic shell and a decorative surface element enveloping said shell, said surface element consisting in a metallic fabric knitted from flat ribbon-like wire to provide a multiplicity of light reflecting facets.

4. A decorative ornament for the purposes described, comprising a substantially rigid base element of desired shape, a decorative surface element consisting in a metallic fabric knitted from flat ribbon-like wire into tubular form and doubled on itself to provide a plurality of cover plies, said base element being enveloped in said thus formed surface element, the open ends of said surface element being gathered together and closed, and a suspension loop connected with one closed end thereof.

5. A decorative ornament for the purposes described, comprising a hollow metallic shell, a decorative surface element adapted to provide a multiplicity of light reflecting facets, said surface element consisting in a metallic fabric knitted from flat ribbon-like wire into tubular form and twisted intermediate its ends and doubled on itself to provide a plurality of cover plies, said shell element being enveloped in said thus formed surface element, the open end of said surface element being gathered together and closed, a wire tie around said gathered closed end, and portions of said wire tie being projected to form a suspension loop.

In testimony, that I claim the invention set forth above I have hereunto set my hand this date 14th day of September, 1927.

RUSSELL B. KINGMAN.
